E. L. COMBS

BAG HOLDER

Filed Dec. 22, 1923

Edgar L. Combs Inventor

By Maura Cameron, Lewis & Clark

Attorneys

UNITED STATES PATENT OFFICE.

EDGAR L. COMBS, OF GWYNEDD, PENNSYLVANIA.

BAG HOLDER.

Application filed December 22, 1923. Serial No. 682,315.

To all whom it may concern:

Be it known that I, EDGAR L. COMBS, a citizen of the United States of America, and a resident of Gwynedd, Pennsylvania, have 5 invented new and useful Improvements in Bag Holders, which invention is fully set forth in the following specification.

This invention relates to a bag holder, and particularly to a bag holder of the knock-down type which may be employed for holding bags while the latter are being filled.

An object of the invention is to provide a strong and inexpensive bag holder. Another object is to provide such a bag holder 15 capable of being collapsed, knocked-down, or folded, into a compact unit such as to occupy but little space in transportation, or when stowed away, and at the same time capable of being easily and quickly set up in condition for use. Further objects of this invention are to provide bag supporting members carrying bag engaging means that greatly facilitate the attachment and detachment of the bags to and from said members; and 20 to provide means for maintaining the bag supporting members in proper relation when the device is in use, and yet so designed that said means may be readily removed when it is desired, thus permitting the holder to be 25 adjusted to compact form for stowing. Other objects will appear more fully hereinafter.

In order that the invention may be readily understood reference is had to the accompanying drawings, illustrating two embodiments of the inventive idea, and wherein—

Fig. 1 is a perspective view of my improved bag holder, illustrating one type of 40 bag engaging means that may be employed.

Fig. 2 is a side elevation illustrating a second embodiment of the invention, and

Fig. 3 is an end view illustrating the bag 45 engaging means shown in Fig. 1 mounted on the supporting structure of Fig. 2.

Referring to the drawings, wherein like numerals refer to like parts throughout the several views, and particularly to Fig. 1, my improved bag holder includes a frame 50 having a bar, a beam 6, and at each end thereof a pair of upright legs or supports 4 removably secured by said bar or beam by any suitable means, as, for example, by screws 5. Spreaders 7 may if desired, be 55 secured at any suitable point to legs 4 to strengthen the same. Pivots secured to

the upper face of bar 6, and at the desired distance apart, are a pair of bag supporting members or rails 8, which are longitudinally grooved as shown. Bag engaging arms or clamp members 8' are hinged to members 8, one on each side of horizontal bar 6, and are provided with tongues 8'' which are adapted to engage the grooves formed in members 8 when arms 8' are moved to bag engaging position. Spring catches 8''' are preferably hinged to the outer ends of arms 8' for securing the latter in bag engaging position. If desired, prongs may be provided in the grooves, and said prongs may be the points of nails driven upwardly through members 8 such prongs to cooperate with arms 8' in holding the bags to be filled.

A spacer 11 is removably secured to the upper surface of bar 6, by means of a screw or bolt 10, said spacer being so formed at its opposite ends that it will engage members 8 and maintain them in parallelism substantially at right angles to bar 6. An opening 12 is provided at any convenient point in the lower surface of bar 6 for a purpose to be described hereinafter.

When assembled for use members 8 are held against pivotal movement by spacer 10 thus insuring that the mouths of the bags 13 to be filled will be held open. When not in use, and it is desired to stow the holder away, spacer 11 may be removed from the upper surface of bar 6 and removably secured to the lower surface thereof by engaging bolt 11 in opening 12. Rails 8 may then be swung on their pivots until substantially parallel with bar 6 and, if desired, uprights 4 may be readily detached from bar 6 thus permitting the device to be stored in a small space and to be readily assembled when needed.

Referring to Figs. 2 and 3, illustrating other embodiments of the present invention, bar 6' is cut away or recessed at 14 at each end on the lower surface thereof. Blocks 16 are pivotally secured to bar 6' by any suitable means, for example, hinges 15. Legs 4' are secured to blocks 16 by means of hinges 17 for pivotal movement in planes at right angles to the plane of movement of blocks 16. Preferably, spreaders 7' are pivotally secured to one leg of each pair of legs 4', as at 18, the opposite end of the spacer being provided with a notch 19 adapted to engage a pin 20 on the other leg. If desired the bag engaging means may comprise a plurality of

- spring clips 21, or, as illustrated in Fig. 3, the arms 8' previously described. When it is desired to stow the device of Figs. 2 and 3, spacer 11 may be removed and secured to the 5 lower surface of bar 6' as illustrated by dotted lines in Fig. 2, and arms or clamps 8⁴ may then be moved until they are substantially parallel with the bar. Spreader 7' may then be moved to the dotted line position illustrated in Fig. 3, legs 4' are moved one toward the other about hinges 17, and then blocks 16 and legs 4' may be swung on their hinges 15 to the position illustrated by dotted lines in Fig. 2.
- 10 15 From the above it will be seen that I have provided a device which is inexpensive to manufacture, one which is rugged in construction, and one which may be quickly stowed away in compact form when not in use. My improved bag engaging arms permit the user to quickly position empty bags in filling position where they will be firmly held.
- 20 25 This device is particularly adapted for use in gardens or yards when it is desired to rake up and remove leaves, twigs, etc. It insures that the bags, for receiving the debris to be collected, will be held with their mouths open thus greatly facilitating work 30 of this character with a consequent saving of time and labor.

What I claim is:—

1. The combination, in a bag holder, of a frame including an approximately horizontal bar or beam and legs for supporting the same; two spaced rails pivotally secured to said horizontal bar or beam and normally positioned to extend across said bar to constitute at each side thereof a pair of approximately horizontal arms each pair adapted to support or suspend therebetween a bag with its upper end open for filling; a bag attaching means associated with each of said arms for detachably securing a bag thereto while it is being filled; means engaging said rails to secure them in their aforesaid normal positions, but adapted to be disengaged from the rails to permit the latter to be turned on their pivots each to a knock-down position approximately parallel to the said bar or beam of the frame.

2. The combination, in a bag holder, of a frame including an approximately horizontal bar or beam and supporting legs pivotally connected to said bar at opposite ends thereof to be swung either to normal supporting position or to a knock-down position approximately along said bar; and a pair of arms secured to and extending transversely with relation to said bar of the frame and adapted to support or suspend a bag with its upper end held open for filling.

3. The combination, in a bag holder, of a frame including an approximately horizontal bar or beam and supporting legs pivot-

ally connected to said bar at opposite ends thereof to be swung either to normal supporting position or to a knock-down position approximately along said bar; two spaced rails pivotally secured to said horizontal bar or beam and normally positioned to extend across said bar to constitute at each side thereof a pair of approximately horizontal arms each pair adapted to support or suspend therebetween a bag with its upper end open for filling; bag attaching means associated with each of said arms for detachably securing a bag thereto while it is being filled; means engaging said rails to secure them in their aforesaid normal positions but adapted to be disengaged from the rails to permit the latter to be turned on their pivots each to a knock-down position approximately parallel to the said bar or beam of the frame.

4. The combination, in a bag holder, of a frame including an approximately horizontal bar or beam and a pair of supporting legs at each end of said bar having pivotal connection to the bar permitting the legs of each pair to be swung either to their normal supporting positions with the legs spread apart at their lower ends, or to a knock-down position with the legs of each pair swung together and also to a position approximately along said bar of the frame; and a pair of arms secured to and extending transversely with relation to said bar of the frame and adapted to support or suspend a bag with its upper end held open for filling.

5. The combination, in a bag holder, of a frame including an approximately horizontal bar or beam and a pair of supporting legs at each end of said bar having pivotal connection to the bar permitting the legs of each pair to be swung either to their normal supporting positions with the legs spread apart at their lower ends, or to a knock-down position with the legs of each pair swung together and also to a position approximately along said bar of the frame; two spaced rails pivotally secured to said horizontal bar or beam and normally positioned to extend across said bar to constitute at each side thereof a pair of approximately horizontal arms each pair adapted to support or suspend therebetween a bag with its upper end open for filling; bag attaching means associated with each of said arms for detachably securing a bag thereto while it is being filled; means engaging said rails to secure them in their aforesaid normal positions but adapted to be disengaged from the rails to permit the latter to be turned on their pivots each to a knock-down position approximately parallel to the said bar or beam of the frame.

6. A bag holder comprising a support, bag supporting members, having grooves

therein, pivotally secured to said support, means secured to said support for maintaining said members in bag supporting position, and bag engaging means comprising
5 arms pivoted to said members, said arms having tongues extending into said grooves when the arms are moved to bag engaging position.

7. A bag holder comprising a support, 10 bag supporting members pivotally secured to said support and having grooves therein,

a plurality of prongs projecting into said grooves, means secured to said support for maintaining said members in bag supporting position, bag engaging arms provided 15 with tongues for engaging said grooves in the bag supporting members and means for pivotally securing said arms to said members.

In testimony whereof I have signed this 20 specification.

EDGAR L. COMBS.
